UNITED STATES PATENT OFFICE.

HOWARD W. GOULD, OF BOSTON, MASSACHUSETTS, ASSIGNOR TO UNITED SHOE MACHINERY COMPANY, OF PATERSON, NEW JERSEY.

SEWING AND INDENTING MACHINE.

SPECIFICATION forming part of Letters Patent No. 680,142, dated August 6, 1901.

Application filed September 1, 1900. Serial No. 28,814. (No model.)

To all whom it may concern:

Be it known that I, HOWARD W. GOULD, a citizen of the United States, residing at Boston, in the county of Suffolk and State of Massachusetts, have invented certain new and useful Improvements in Sewing and Work-Indenting Machines; and I do hereby declare the following to be a full, clear, and exact description of the invention, such as will enable others skilled in the art to which it appertains to make and use the same.

The present invention relates to an improvement in sewing-machines, and more particularly to that class of sewing-machines which employ stitch-forming mechanism and work-indenting devices for sewing and pricking up the seam at one operation. In most sewing-machines of this class it has been found necessary in practical work to provide some means for correcting the position of the work-indenting tool to compensate for accidental variations in the length of the stitches. Furthermore, in most prior machines of this class the work-indenting tool engaged the work at a distance from the work-piercing implement, with the result that in sewing curved seams the indentations being normal to the curve at the point where the work-piercing implement entered it were inclined to the curve where the indentations were made. It has also been proposed to cause the work-indenting tool to engage the stitch at the needle-hole after the needle had left the work, and mechanism independent of the stitch-forming mechanism was provided to operate the work-indenting tool in proper timed relation to the stitch-forming mechanism. As thus constructed the machines were complicated by the large number of parts and the delicate mechanism required to secure good results.

The object of my invention is to produce a machine of this class in which the work-indenting tool engages the work transversely to the line of the seam and while the work-piercing implement is in the work, whereby I am enabled to dispense with the corrective devices or independent actuating devices for the tool and whereby the indentations are always normal to the line of the seam, and, furthermore, to improve machines of this class in other respects hereinafter pointed out.

My invention consists in the improvement in sewing-machines hereinafter described and claimed.

In the accompanying drawings, Figure 1 is 55 a front side elevation, and Fig. 2 is a front end elevation, of a sewing-machine embodying the preferred form of my invention. Fig. 3 is a sectional elevation of Fig. 1, showing the thread-measurer and its supporting and 60 operating means. Fig. 4 is a bottom plan of the thread-measurer and its supporting means. Fig. 5 is an enlarged side elevation of the feed-cam. Fig. 6 is a longitudinal section through a piece of work in the line of the 65 seam, showing the needle and the work-indenting tool in engagement with the work. Fig. 7 is a section on line *y y*, Fig. 6; and Fig. 8 is a side elevation of the needle.

My invention consists in the mechanism 70 for forming a seam of stitches, comprising a work-piercing implement, such as a needle or awl or the like, and a work-indenting tool having its work-engaging end located in the plane of the work-piercing implement and transversely to the line of the seam, acting to indent the work while the work-piercing implement is in the work, together with means for supporting and operating the parts in timed relation to each other to form a series of 80 stitches in the work and to make indentations in the work transversely to the line of the seam.

My invention is not limited to any particular kind of sewing-machine, for it may be embodied in the fair-stitch machine, the eye-pointed-needle lock-stitch machine, the hook-needle chain-stitch machine, the hook-needle lock-stitch machine, &c., without departure therefrom. The gist of my invention resides 90 in the combination, with any form of stitch-forming mechanism employing a work-piercing implement, of an independently-supported work-indenting tool operating to indent the work in the plane of the work-piercing 95 implement transversely to the line of the seam while the work-piercing implement is in the work.

My invention is not limited to the use of any particular kind of work-piercing implement, but comprehends in its broader aspects any form of such implement, whether it be a

needle, an awl, a feed-point, or the like, nor is my invention limited to the use of any particular form of work-indenting tool, as any suitable tool may be used.

5 I have shown my invention as embodied in a fair-stitch sewing-machine, in which the stitch is formed by successively forcing bights of the thread into successive holes in the material, and I prefer this embodiment of my invention, because in the class of work done by this machine it is desirable to reduce to a minimum the number of operations on a shoe.

The illustrated embodiment of my invention is described as follows:

15 The frame A supports the parts of the machine in the manner hereinafter described.

The needle N, the looper L, and the thread-measurer M constitute the stitch-forming mechanism. The work-support S operates 20 normally to press the work up toward the devices operating thereon and to hold it there during the performance of their stitch-forming and work-indenting operations and during the feed of the work and to release it during 25 the return movement of the needle and work-indenting tool. The needle-rest R supports and guides the needle in the usual manner. The work-indenting tool T embraces the needle and is provided with two wedge-shaped work-engaging edges located in the 30 plane of the needle and transversely to the line of the seam and constitutes principally a work-indenting tool and incidentally a needle guide or support, and it also contributes 35 to the feeding of the work. The presser-foot P (being substantially the same as the presser-foot described in the patent to Mower and Coupal, No 641,719, dated January 23, 1900) operates to engage and hold the work against 40 the work-support during the first part of the downward movement of the needle and to release the work during the last part of such downward movement, so as to allow the work to be fed. The operation of these devices is 45 as follows: Assuming the parts to be in the position shown in the drawings, the needle and work-indenting tool move rearwardly (to the left, as shown in Fig. 2) and feed the work, then the presser-foot P descends 50 and holds the work against the work-support S, the needle N and the work-indenting tool T rise and move forward, then the looper L lays the thread in the hook of the needle, and the thread-measurer M moves to 55 the left from the position which it occupies as shown in Fig. 1 to a position approximately under the needle, where it enters the bight of thread between the hook of the needle and the work. It then moves rearwardly (to the left, as seen in Fig. 2) and measures off a bight of thread sufficient for 60 the next stitch to be formed, and at the same time the needle descends and penetrates the work, the measurer having moved out from under it, and carries down into the work a bight of thread to form a stitch, the thread-measurer M in the meantime withdrawing

from the bight to permit the needle to carry thread down into the work, as shown in Fig. 6. Before the needle has completed its downward movement the work-indenting tool T engages the work and forms two indentations therein upon opposite sides of the seam of stitches and in the plane of the needle, being substantially at right angles to the line 70 of the seam. Just before the completion of the downward movement of the needle the presser-foot P is raised and the work is thereby released, so that the rearward movement of the needle and work-indenting tool will 80 feed the work a distance equal to the length of a stitch. It will be observed that the work-indenting tool is accurately located with relation to the needle-hole and that whatever may be the variations in the length of the 85 stitches, due to whatever cause, whether accidental or intentional, the indentations will always be located exactly opposite the needle-holes. It will be seen that the work-indenting tool cooperates with the needle to 90 feed the work and that it also forms a guide which supports the needle. It will also be observed that the line of the indentation made by the tool is always normal to the line of the seam, whether that line be straight or curved. 95

I will now describe the mechanisms for operating the needle, looper, thread-measurer, presser-foot, work-indenting tool, and for actuating the needle and work-indenting tool to feed the work.

The needle N is carried in the needle-bar n, being secured therein in the usual manner, which bar is mounted in bearings in the head A', pivoted at a¹ to the front end of the frame A of the machine. The needle-rest R is also carried by the needle-bar in the usual manner. Adjustably secured to the needle-bar is a block n', to which is pivoted one end of the pitman n², the other end of which embraces a crank-pin in the end of the main shaft B, supported in suitable bearings in the frame A of the machine. Rotations of the shaft thus reciprocate the needle-bar.

The work-indenting tool T is mounted in the tool-bar t, which is supported in bearings 115 in the head A' parallel to the needle-bar n. The tool T is provided with a shank t', which is received in a hole in the tool-bar t, being secured in adjustable position therein by the set-screw t². A collar t³ is secured to the tool-bar t below the lower bearing in the head A', and it serves to limit the upward motion of the tool-bar by its engagement with the under surface of the head. Upon the tool-bar is adjustably secured the block 120 t⁴. Between the lower bearing of the tool-bar t in the head A' and the block t⁴ is interposed a spring t⁵, which encircles the tool-bar and normally operates to lift the tool-bar. The upper surface of the block t⁴ is adapted 125 to be engaged by the block n' as that block approaches the limit of its downward throw, so that during the latter part of the downward movement of the needle the block n' is

in engagement with the block t^4 , and the tool T is thereby forced downward with the needle to make its work-indenting stroke.

The looper L is secured to the lower end of the looper-lever l by the set-screw l' . The looper-lever l is pivoted at l^2 in a fixed part of the frame A of the machine, and it bears upon its upper end a cam-roll l^3 , which engages the cam-path l^4 of the cam l^5 , mounted on the front end of the shaft B . The cam-path is such as to impart to the looper the movements across the path of movement of the needle to lay a bight of thread in the barb of the needle as it returns from its feeding stroke.

The thread-measurer M is mounted on a lever m , being secured thereto by means of the bolt m' . The lever m is pivoted upon a slide m^2 , mounted in a slideway m^3 , fixed to the bracket m^4 on the frame A of the machine. The thread-measurer is moved to the right and left, as seen in Fig. 1, by means of the lever m^5 , pivoted at m^6 upon the bracket m^4 . The lever m^5 is slotted at m^7 to receive a pin m^8 , projected from the side of the slide m^2 . At the other end of the lever m^5 there is supported a cam-roll m^9 , which engages a cam-path m^{10} in a cam m^{11} , mounted on the shaft B . The cam-path is such that it will move the thread-measurer to the left, as seen in Fig. 1, to engage the bight of thread after the thread has been laid in the hook of the needle by the looper. The lever m is moved to impart to the thread-measurer M its forward movement by means of a spring m^{12} , which is supported at one end upon a projection m^{13} from the guideway m^3 and bears at the other end against the lever m . The lever is moved rearwardly to measure off thread by means of the lever m^{14} , pivoted at m^{15} upon the bracket m^4 . The lower end of the lever m^{14} engages a projection m^{16} , adjustably secured to the lever m by the cap-bolt m^{17} . The other end of the lever m^{14} carries a cam-roll m^{18} , which engages a cam-path m^{19} in the cam m^{11} , above referred to. The cam-path m^{19} is such that after the thread-measurer M has been moved to the left, as seen in Fig. 1, to enter the bight of thread it will move the thread-measurer rearwardly to measure off the bight of thread required to form the next stitch. It will be noted that adjustment of the projection m^{16} regulates the amount of thread measured off by the thread-measurer.

The presser-foot P has a work-engaging end p , which is located in front of the needle. The presser-foot P is of gooseneck shape and secured in the usual manner at p' to the presser-bar p^2 , which is mounted in suitable bearings in a stationary part of the head of the machine. A spring p^3 , engaging at one end a collar p^4 , adjustably secured to the presser-bar p^2 by the set-screw p^5 , and at the other end engaging the upper bearing p^6 , normally tends to force the presser-bar down-

ward, and thereby to hold the presser-foot in engagement with the work. A threaded collar p^7 and nut p^8 are mounted upon the upper threaded end of the presser-bar, so that they may be adjusted up and down thereon and secured in any desired position. A lever p^9 , pivoted at p^{10} to the head A' , bears at one end against the under side of the collar p^7 and at the other side projects under a collar p^{11} , adjustably secured to the needle-bar n by the set-screw p^{12} . The adjustment of these parts is such that when the needle begins its downward movement the presser-foot, bearing down against the work-support, securely holds the work thereon, and that after the needle has descended through a part of its stroke then the collar p^{11} will engage the lever p^9 and cause it to raise the presser-foot, so that the ensuing feed movement of the needle and work-indenting tool may carry the work freely rearward. Then upon the beginning of the upward stroke of the needle the presser-foot again drops on the work. While the needle and work-indenting tool are making their return stroke the work-support S is released and pressed upward against the presser-foot, so as to compensate for variations in thickness of the work.

The head A' , which constitutes the support for the needle-bar n and tool-bar t , is actuated to impart to those instrumentalities their work-feeding movement by means of the cam a , mounted upon the main shaft B of the machine. A lever a' , pivoted at a^2 upon a fixed part of the frame A of the machine, is provided at its opposite end with a cam-roll a^3 , which engages the cam-path a^4 on the cam a . The rotation of the cam a imparts lateral oscillations to the lever a' . The lever a' is provided with an arc-shaped slot a^4 , which is engaged by a block a^5 , mounted upon an arm a^6 , pivoted at a^7 in the head A' . The position of the block a^5 in the slot a^4 determines the amplitude of oscillation which shall be imparted to the head A' by the cam a . When the block is raised, it moves to a part of the slot which partakes of a wider amplitude of movement, and so the movements imparted to the head A' when the block is in this part of the slot are greater than when the block is in the position shown in the drawings. The position of the block a^5 in the slot a^4 is adjusted by providing the shaft a^8 , to which the lever a^6 is secured, with a worm-wheel a^9 , which is engaged by a worm a^{10} , mounted upon a shaft a^{11} , carried in suitable bearings in the bracket a^{12} , secured to the head A' , and provided on its outer end with a thumb-head a^{13} , so that by turning the shaft a^{11} the length of the feed may be varied. The shape of the cam-path a^4 is such as to cause the head A' to stand still during the formation of the stitch and the indenting of the work and to move forward to feed the work after the completion of the stitch-forming and work-indenting operations and then

backward to return those parts to their original position after they have retreated from the work.

I am aware of the patent to Hadaway, No. 5 616,314; but my invention is clearly distinguished therefrom in many respects, of which it is sufficient here to advert only to the following: First, the work-indenting tool in the said patent engages the work after the needle 10 has withdrawn therefrom, so that if the work was pressed through the machine the tool would engage the work beyond the needle and defective work would result therefrom, and, second, the timed relation of the parts in 15 the machine of said patent is such that independent mechanism is required to operate the work-indenting tool, whereas in carrying out my invention, since the work-indenting tool engages the work simultaneously with the 20 work-piercing implement, the indentations are and must be properly positioned with relation thereto, in addition to which I am enabled in the preferred embodiment of my invention to operate the work-indenting tool 25 from the stitch-forming mechanism.

Having thus described my invention, I claim as new and desire to secure by Letters Patent of the United States—

1. A sewing-machine, having, in combination, 30 stitch-forming mechanism, comprising a work-piercing implement, an independently-supported work-indenting tool having its work-engaging end located in the plane of the work-piercing implement and transversely to the line of the seam, acting to indent the work while the work-piercing implement is in the work, and means for actuating the parts, substantially as described.

2. A sewing-machine, having, in combination, 40 stitch-forming mechanism comprising a work-feeding tool, an independently-supported work-indenting tool having its work-engaging end located in the plane of the feeding-tool and transversely to the line of the seam, acting to indent the work while the work-feeding tool is in the work, and means for actuating the parts, substantially as described.

3. A sewing-machine, having, in combination, 50 stitch-forming mechanism comprising a needle, an independently-supported work-indenting tool having its work-engaging end located in the plane of the needle and transversely to the line of the seam, acting to indent the work while the needle is in the work, and means for actuating the parts, substantially as described.

4. A sewing-machine, having, in combination, 60 stitch-forming mechanism comprising a work-piercing implement, an independently-supported work-indenting tool movable with the work-piercing implement having its work-engaging end located in the plane of the work-piercing implement and transversely to the line of the seam, acting to indent the work while the work-piercing imple-

ment is in the work, and means for actuating the parts, substantially as described.

5. A sewing-machine, having, in combination, 70 stitch-forming mechanism comprising a work-feeding implement, an independently-supported work-indenting tool movable with the work-feeding implement having its work-engaging end located in the plane of the feeding implement and transversely to the line of the seam, acting to indent the work while the work-feeding implement is in the work, and means for actuating the parts, substantially as described.

6. A sewing-machine, having, in combination, 80 stitch-forming mechanism comprising a needle acting to feed the work, an independently-supported work-indenting tool movable with the needle having its work-engaging end located in the plane of the needle and 85 transversely to the line of the seam, acting to indent the work while the needle is in the work, and means for actuating the parts, substantially as described.

7. A sewing-machine, having, in combination, 90 stitch-forming mechanism comprising a needle, an independently-supported work-indenting tool embracing the needle and acting to indent the work transversely to the line of the seam, and means for actuating the 95 parts in timed relation to each other so that the indenting tool engages the work after the needle has entered the work and before the needle has completed its downward movement, substantially as described.

8. A sewing-machine, having, in combination, 100 stitch-forming mechanism, comprising a needle, an independently-supported work-indenting tool embracing the needle acting to indent the work transversely to the line of the seam, a thread-finger acting to engage and measure off thread for the next stitch and means for actuating the parts, substantially as described.

9. A sewing-machine, having, in combination, 110 stitch-forming mechanism comprising a needle, an independently-supported work-indenting tool embracing the needle acting to indent the work transversely to the line of the seam, a thread-finger acting to engage the 115 thread and to move rearwardly to measure off thread for the next stitch and means for actuating the parts, substantially as described.

10. A sewing-machine, having, in combination, 120 stitch-forming mechanism comprising a needle, an independently-supported work-indenting tool embracing the needle acting to indent the work transversely to the line of the seam, a thread-finger acting to engage 125 and measure off thread for the next stitch, and means for actuating the parts in timed relation to each other so that the indenting tool engages the work after the needle has entered the work and before the needle has 130 completed its downward movement, substantially as described.

11. A sewing-machine, having, in combination, stitch-forming mechanism comprising a needle, an independently-supported work-indenting tool embracing the needle acting 5 to indent the work transversely to the line of the seam, a thread-finger acting to engage the thread and to move rearwardly to measure off thread for the next stitch, and means for actuating the parts in timed relation to each 10 other so that the indenting-tool engages the work after the needle has entered the work and before the needle has completed its downward movement, substantially as described.

12. A sewing-machine, having, in combination, stitch-forming mechanism, comprising a needle, a needle-bar, a work-indenting tool, a tool-bar, a spring normally acting to lift 15 the tool-bar, connections between the needle-bar and tool-bar acting to depress the tool- 20 bar with the downward stroke of the needle-

bar, and means for actuating the parts, substantially as described.

13. A sewing-machine, having, in combination, stitch-forming mechanism, comprising a needle, a needle-bar, a work-indenting tool, 25 having its work-engaging end located in the plane of the needle and transversely to the line of the seam, a tool-bar, a movable support for the bars, means for moving the support while the needle and work-indenting 30 tools are in engagement with the work to feed the work, and means for actuating the parts, substantially as described.

In testimony whereof I affix my signature in presence of two witnesses.

HOWARD W. GOULD.
